UNITED STATES PATENT OFFICE.

JAMES O. GILMORE, OF DICKERSON RUN, PENNSYLVANIA.

RAIL-CLAMP TIE PLATE.

Application filed October 12, 1927. Serial No. 225,821.

This invention relates to a rail clamp tie plate and has for its primary object the construction of a clamp that may be more effectively secured to a rail and when in place will have an interlocking engagement with a rail tie so as to positively hold the rail tie, clamp and rail in their proper associated relations.

An object of the invention is the construction of a rail clamp of two component parts 10 adjustably related and having an interlocking connection with each other whereby the clamp may be effectively brought into engagement with the rail irrespective of the exact size of the latter.

Another object of the invention is the 15 novel manner of constructing and associating the clamp plate and the base plate so that they may have an adjustable interlocking connection for adapting the clamp to a rail 20 joint, suitably placed ribs enabling the clamp to have an interlocking engagement with the rail tie.

Besides the above, my invention is distinguished in the use of a pair of companion 25 plates adjustably related and having an interlocking connection and further provided with a plurality of openings for the reception 30 of securing elements which not only secures the clamp to a tie, but positively prevents disengagement of the plates.

With these and other objects in view the invention will be better understood from the following detailed description, taken in connection with the accompanying drawing, 35 wherein:

Figure 1 is a top plan view,

Figure 2 is a side elevation,

Figure 3 is a bottom plan view, and

Figure 4 is a cross sectional view.

Again referring to the drawing illustrating one of the many constructions of my invention, it will be noted that my improved rail clamp consists of two major parts herein-after designated as a base plate 1 and a clamp 40 plate 2, adjustably associated and having an interlocking connection with each other so as to provide a rigid connection therebetween. The base plate 1 is elongated and provided with an overhanging and transversely extending lip 3 for engagement with the base B

of the rail C. This base plate 1 is further provided on its under surface with a plurality of sharpened ribs 4 arranged at an angle to each other and preferably diverging from a central point as indicated at 5 so that when the ribs are brought into a biting engagement with the tie, the latter will be positively associated with the former thereby preventing relative shifting of the plate and tie, and as the clamp has an effective clamping engagement with the rail, it will be appreciated that the tie, clamp and rail are rigidly connected together as a unit.

The clamp plate 2 is also provided with an overhanging lip 6 co-acting with the lip 3 to effectively engage the base of the rail as clearly shown in Figure 4. This plate 2 is further provided with a dove tail key or rib 7 slidably arranged in a correspondingly shaped slot 8 in the base plate. The clamp plate 2 is of considerable width and extends transversely of the base plate 1. It rests upon the upper surface of the base plate 1 and extends inwardly and outwardly beyond the slot 8. The rib 7 is arranged between the side edges of the clamp plate 2, and extends from one end of the clamp plate to the other end thereof. Referring to Figure 1, it will be noted that the slot and key are arranged at an inclination relative to the rail so that when the clamp plate is slid in a predetermined direction an effective binding engagement is brought about between the clamp plate and the base of the rail, whereas movement in the opposite direction enables the clamp plate to be readily disconnected from the base plate. For the purpose of preventing accidental displacement of the clamp plate relative to the base plate and to produce a more effective engagement between the clamp and the tie, I have illustrated the clamp plate provided with a hole 9 aligning with a slot 10 in the base plate for the reception of a securing element, such as a spike. The base plate in addition is provided with holes 11 for the reception of securing elements. The hole 9 and slot 10 are arranged inwardly of the rib 7 and slot 8, and the slot extends transversely of the base plate 1.

In the application of the clamp to a rail, the base plate is brought into flat engagement 100

with the rail tie with the lip 3 overhanging the base of the rail. Sliding of the key into the slot brings the clamp plate into proper engagement with the base of the rail and upon striking this clamp plate a tight effective grip can be established between the clamp plate and the base of the rail. In the parts just described, the driving of a securing element through hole 9 and slot 10 effectively secures the clamp plate to the base plate and also to the rail. Upon pressure being brought to bear upon the rail the sharpened ribs will be forced into the rail tie and because of their angular relation an effective connection is established between the base plate and the tie which will positively prevent relative displacement of the clamp and tie and as heretofore stated the clamping action between the clamp and the rail will positively prevent relative movements therebetween. Thus in a very inexpensive and substantial manner I am able to bring about a very effective engagement between the rail tie, a rail and a clamp plate for positively preventing relative displacement thereof.

It is of course, to be understood that the base plate as well as the clamp plate may be designed in other forms than illustrated and may be associated in other relations and besides various other types of securing elements may be used to effectively lock the clamp plate to the base plate, therefore, I do not desire to be limited in protection in any manner except as set forth in the following claim.

35. What I claim is:

A rail clamp tie plate comprising an elongated base plate having a rail receiving portion and provided with a transversely extending rail engaging lip overlying said portion, the greater part of the base plate extending inwardly beyond the rail and provided with a dovetail slot extending from an inner corner of said rail receiving portion to a point close to the diagonally opposite corner of said greater part, a broad flat clamp plate resting upon said greater part and provided with a rail engaging lip overlying said rail receiving portion, and a dovetail rib formed on the lower side of the clamp plate and entering said slot and extending between diagonally opposite corners of the clamp plate, the base plate being provided between the rail and slot with a transversely extending slot, and the clamp plate being provided between the rail and rib with an opening registering with said slot.

In testimony whereof I affix my signature.
JAMES O. GILMORE.
